UNITED STATES PATENT OFFICE.

JOHN F. O'CONNOR, OF CHICAGO, ILLINOIS, ASSIGNOR TO W. H. MINER, INC., OF CHICAGO, ILLINOIS, A CORPORATION OF DELAWARE.

HAND BRAKE.

Application filed May 20, 1926, Serial No. 110,373. Renewed April 23, 1928.

This invention relates to hand brakes. One object of the invention is to provide a simple and efficient hand brake, wherein means are provided for rapidly taking up 5 the slack in the brake chain, and subsequently increasing the ratio of leverage to exert greater force in the final application of the brakes.

Another object of the invention is to provide a hand brake of this character wherein 10 lever means are interposed in the brake rigging between the brake winding staff and the brake mechanism proper, and resiliently held against movement in an operative direction, said lever means permitting free travel 15 of the rigging with respect thereto, while quiescent, during taking up of the slack, and being automatically operated by increase of tension in the rigging to effect swinging 20 thereof to increase the power ratio during final application of the brakes in conjunction with mechanism for arresting travel of said rigging with respect to said lever means, which mechanism is automatically 25 moved to operative position or released therefrom by said rigging, dependent upon variations of tension therein.

Other further objects and advantages of the invention will more fully and clearly 30 appear from the description and claims hereinafter following.

In the drawing forming a part of this specification, Fig. 1 shows fragments of a car structure, illustrating a top plan view 35 of the invention as applied thereto, with parts of the same shown in section. And Fig. 2 is a part sectional, and part elevational view of the invention, taken substantially on the line 2-2 of Fig. 1.

40 In said drawing, 4 indicates a fragment of the end sill of a car, which is provided with a depending stirrup 5 in which is mounted the usual winding staff 6, said sill 4 being provided with an inwardly extending bracket 7 upon which the lever means are mounted.

The lever means comprise spaced bars 8 and 9 arranged in substantially parallel relation, one end portion of the bar 9 having 45 an angular extension 10, a portion of which rests upon the upper surface of the bracket 7, while the bar 8 has one end arranged to rest upon the extension 10, a pivot pin 11 extending through the end of the bar 8, the 55 extension 10, and the bar 9, said pin being

held in position by the usual cotter pin 12, the arrangement affording a fulcrum for the lever means adjacent one end thereof upon the car structure. The bars 8 and 9 are connected together, and contain operative parts hereinafter referred to, said bars being substantially of the same length, and the free ends thereof being confined to limited swinging movement in a horizontal direction by 60 guide means indicated at 13. Said guide means include spaced horizontally extending guiding surfaces 14 which confine the end of the lever means to horizontal movement, the swinging movement of the free end of the lever means being limited in an 65 inward direction by a stop 15, and in an outward direction by a stop 16.

Adjacent the free ends of the bars 8 and 9, there is provided a carrier 17 which is disposed between the bars 8 and 9 and comprises spaced elongated plates 18 and 19, which are held in spaced relation by means of a spacing member 20, said plates being secured together at one corner by a rivet 21. The spacing member 20 is disposed adjacent 70 another corner of the carrier as shown, and extending through said spacing member, the plates 18 and 19, and the ends of the bars 8 and 9, is a pivot pin 22, which pivotally connects the carrier 17 for swinging movement 75 with reference to the bars 8 and 9. At the free end portion of the carrier 17 opposite the pivot 22, there is mounted between the plates 18 and 19 a sheave 23, which is rotatably supported upon its hub 24, said sheave 80 being provided with circumferentially arranged recesses, indicated at 124, for the reception of the links of the chain forming the brake rigging, as hereinafter referred to, said sheave operating as a sprocket wheel in 85 the device. Ratchet wheels 25-25 are provided at each side of the sheave 23, and are fixed with respect to said sheave and rotate in unison therewith.

Mechanism is provided which normally 100 pulls said carrier in a direction away from the lever means, said mechanism including a connecting rod 26 which is pivotally connected to the carrier 17 at a point intermediate, and to one side of, the pins 22 and 24, as 105 shown, said connecting rod having at its outer end a cross head 27 which is slidably mounted upon the arms 28-28 of a yoke, the free ends of the arms 28 being connected by a plate 29 which forms a spring abutment, 110

the plate 29 being held upon the arms 28-28 by suitable nuts. A coiled spring 30 is disposed about the connecting rod 26, one end of said spring bearing against the cross head 27 and the opposite end of the spring bearing against the plate 29. The bight 31 of the yoke is connected to a fixed part of the car structure, indicated at 32.

Affixed to the lever means, adjacent the 10 ratchet wheels 25-25 mounted upon the carrier 17, is a bracket having angular portions 33-33 which are riveted to the bars 8 and 9 of the lever means, and which are connected by a web 34, said web on its inner surface, 15 between the bars 8 and 9, being provided with a rib 35 which acts as a fixed pawl, adapted to cooperate with the ratchet wheels 25-25 in certain positions to prevent counter-clockwise rotation of the ratchet wheels 25-25, and of the sheave 23.

Rotatably mounted upon the lever means, adjacent to but spaced from the pivot or fulcrum of said lever means, upon a pin 36 extending through the bars 8 and 9, is a plain 25 sheave 37. The brake rigging indicated at 38, which is usually in the form of a chain, has one end connected to the winding staff 6, extends thence over the sheave 23, around the sheave 36, and thence to the brake mechanism proper, not shown.

In the normal position of the parts, the lever means are drawn inwardly away from the end sill 4 by the spring 30, and associated parts, and the carrier member 17 is also drawn away from the lever means as indicated in Fig. 1, so as to free the ratchet wheels 25-25 from engagement with the fixed pawl 35. Upon clockwise rotation of the winding staff 6, to take up the brake rigging 38, said rigging travels freely over the sheaves 37 and 23, due to the fact that the tension in the rigging is relatively small and not sufficient to overcome the strength of the spring which maintains the lever in 45 its fully released position. Upon increased resistance being developed in the brake rigging, due to the brake shoes coming into contact with the wheels, the force exerted by the spring 30 will be overcome, causing the free end of the carrier 17 to move inwardly toward the lever, until the ratchet wheels 25 come into engagement with the fixed pawl 35, thereby preventing counter-clockwise movement of the sheave 23, after which the 55 rigging is taken up to effect full application of the brakes through swinging movement of the lever means along the arc described by the sheave 37, as indicated in dotted lines in Fig. 1, resulting in a great increase in power. When the brake staff 6 is released, the action of the spring 30 is such as to retract the lever and carrier to fully released position, disconnecting the ratchet wheels 25-25 from the holding pawl 35, resulting 60 in full unwinding of the brake rigging from

the staff 6 and consequent full release of the brake shoes.

While I have herein shown and described what I now consider the preferred manner of carrying out my invention, the same is 70 merely illustrative, and I contemplate all changes and modifications that come within the scope of the claims appended hereto.

I claim:

1. In a hand brake, the combination with 75 winding means and the brake mechanism proper; of lever means interposed between said winding means and said brake mechanism proper, said lever means being arranged to swing about one end portion thereof as a fulcrum and being provided with spaced guides thereon, one of the same being arranged adjacent the fulcrum point of said lever means, and the other connected adjacent the free end portion of said lever means, said second guide being bodily movable with reference to said lever means; and rigging extending from said brake mechanism proper to the guide means adjacent 80 said fulcrum, and over the guide means adjacent the free end of said lever means and thence to said winding means, said rigging being arranged to normally travel freely with respect to said guide means while said lever means are quiescent to take up the 85 slack, and thereafter cooperating with said lever means to automatically effect swinging of the same to increase the power ratio; and resilient means connected to said second guide means and to a fixed point for 90 urging said second guide and lever means toward released position.

2. In a hand brake, the combination with 95 winding means and the brake mechanism proper; of lever means interposed between said winding means and said brake mechanism proper, said lever means being arranged to swing about one end portion thereof as a fulcrum and normally urged to released position, said lever means being provided with spaced guides thereon, one of the same being arranged adjacent the fulcrum point of said lever means, and the other adjacent the free end portion of said lever means; rigging extending from said brake mechanism proper to the guide means adjacent 100 said fulcrum, and over the guide means adjacent the free end of said lever means and thence to said winding means, said rigging being arranged to normally travel freely with respect to said guide means to take up the slack while said lever means are quiescent and effect swinging movement of said lever means when the tension in said rigging increases and means for 105 arresting travel of said rigging with reference to said lever means upon swinging movement of the latter, said arresting means being automatically controllable by movements of said rigging.

3. In a hand brake mechanism, the combination with a winding staff and brake mechanism proper; of lever means interposed between said staff and said mechanism and adapted to swing about one end portion thereof as a fulcrum; a carrier pivotally mounted on said lever means adjacent the free end portion thereof, said carrier being provided with guide means thereon; 5 guide means adjacent the fulcrum point of said lever means; means co-acting with said carrier to normally urge said carrier away from said lever means; rigging extending from said brake mechanism proper over the 10 guide means adjacent the fulcrum point of said lever, thence over the guide means on said carrier to said brake winding means; and means for arresting and permitting movement of said rigging over said guide 15 means dependent upon variations of resistance in said rigging.
4. In a hand brake, the combination with a winding staff and brake mechanism proper; of lever means interposed between 20 said staff and said mechanism and adapted to swing about one end portion thereof as a fulcrum; a rotatable sheave mounted on said lever means adjacent the fulcrum thereof; a carrier pivotally mounted on said lever 25 means adjacent the free end portion thereof, said carrier being provided with a rotatable sheave, ratchet members on said lever means and said last mentioned sheave adapted to co-act in certain positions to arrest 30 rotation of said sheave; resilient means connected to said carrier and normally maintaining said ratchet means and said lever in fully released position; brake rigging extending over the sheave on said lever means, thence under the sheave on said carrier to said winding means. 35
5. In a hand brake, the combination with a winding staff and brake mechanism proper; of lever means interposed between said staff and said mechanism and adapted to swing 40 about one end portion thereof as a fulcrum; a rotatable sheave mounted on said lever means adjacent the fulcrum thereof; a carrier pivotally mounted on said lever means adjacent the free end portion thereof, said 45 carrier being provided with a rotatable sheave; ratchet members on said lever means and said last mentioned sheave adapted to co-act in certain positions to arrest rotation of said sheave; resilient means connected to 50 said carrier and normally maintaining said ratchet means and said lever in fully released position; brake rigging extending over the sheave on said lever means, thence under the sheave on said carrier to said 55 winding means; and means for guiding the free end of said lever means within pre-determined limits. 60

In witness that I claim the foregoing I have hereunto subscribed my name this 17th 65 day of May, 1926.

JOHN F. O'CONNOR.
